(57) CLAIM

The ornamental design for a foldable ring light, as shown and described.

DESCRIPTION

FIG. 1 is a first perspective view of a foldable ring light showing my design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the foldable ring light thereof; and,

FIG. 10 is a perspective view of further another state of the foldable ring light thereof.

The broken lines shown in the drawings depict portions of the foldable ring light in which the design is embodied that form no part of the claimed design.
